UNITED STATES PATENT OFFICE.

BURTON L. HUNTLEY, OF MINNEAPOLIS, MINNESOTA, ASSIGNOR, BY DIRECT AND MESNE ASSIGNMENTS, TO KREAMPAK CARTON CO., OF MINNEAPOLIS, MINNESOTA, A CORPORATION OF DELAWARE.

ICE-CREAM-CARTON FILLER.

Application filed September 10, 1925. Serial No. 55,517.

My present invention relates to that general type of ice cream carton fillers disclosed and claimed in my application for Letters Patent of the United States, Serial Number 5 19,833, filed April 1, 1925, and entitled "Ice cream carton fillers," but is not limited to the particular construction illustrated in said application. In ice cream carton fillers involving cylindrical casings that are insertable 10 into the body of ice cream to fill cartons, a great deal of difficulty has been experienced in removing the carton from the cylindrical casing after the carton has been filled with ice cream. After very considerable experience, 15 I have discovered a remedy for the above defect. I have found that in the operation of filling the carton with cream, the carton will be expanded into tight or close engagement with the cylindrical shell of the 20 carton filler, so that partial vacuum will be produced between the carton and the metallic shell and such partial vacuum will cause the filled carton to be tightly held in the shell. I have further found that, by 25 providing the metallic shell of the carton filler in its cylindrical surface with a large number of small air passages, the partial vacuum will be released and the filled carton may be readily removed from the metallic shell. This, while a very simple expedient, 30 has removed a very serious obstacle in the use of ice cream carton fillers.

In the accompanying drawings, which illustrate the invention, like characters indicate like parts throughout the several views.

Referring to the drawings:—

Fig. 1 is a perspective showing an ice cream carton filler designed in accordance with or embodying my present invention; 40 Fig. 2 is a horizontal section taken on the line 2—2 of Fig. 1;

Fig. 3 is a horizontal section on the line 3—3 of Fig. 1, the carton being removed;

Fig. 4 is an axial section of the cylindrical shell of the carton filler; and

Fig. 5 is a fragmentary section on the line 5—5 of Fig. 1.

The character A indicates a cylindrical paper carton adapted to be filled with ice cream. This paper carton is arranged to be placed within a cylindrical metal shell 3, which, at its upper end, is arranged to be interlocked to the depending annular flange of a cylinder head 4, by means of bayonet

joints 5. The cylinder 4 is provided with 55 an axial stem 6 provided at its upper end with a cross-bar 7.

When the cylinder head is removed, the carton A is adapted to be inserted into the cylindrical casing 3 with its upper end projecting above the same and with its lower end resting on an annular stop flange or shoulder 8 formed by the upper and inner portion of a toothed band 9. The teeth of the band 9 are given a "set," some radially 60 inward and some radially outward. The ice cream carton filler, so far just described in detail, is that of the structure disclosed and claimed in my prior application above identified; but it will be understood that, 65 so far as this invention is concerned, the filler may be of any type wherein a cylindrical or approximately cylindrical metal shell is employed as a container for a carton to be filled with ice cream.

As above indicated, the salient feature of this invention consists in providing the cylindrical shell 3, (or similar shell used for the purpose of filling ice cream cartons with ice cream or other plastic material), with a 80 multiplicity of air-venting passages. The air-venting passages may be circumferentially and longitudinally spaced air-venting ports or holes, or they may be longitudinal internal grooves; and in the drawings, I 85 have shown both species of said air-venting passages.

The air holes or relief ports should be located close enough together to admit air to all of the surface contact between the 90 carton and shell or to completely break up the partial vacuum that may exist between the carton and shell. The longitudinal internal grooves 10^a probably serve the venting purpose better than the holes, but both 95 may be used together to advantage, although the general purpose may be accomplished by the use of either. These air-venting passages break up the vacuum or suction between the carton and shell and make the removal of the former from the latter a very easy matter, whereas, without these air holes, the removal of the filled carton would be a very difficult matter.

It is very desirable that the person using 105 the filler be able to see when the carton has been completely filled and, hence, I have provided the head 4 with circumferentially

spaced segmental sight openings 11 covered with transparent material 12, such as mica, celluloid or glass, and between these sight openings I have shown air discharge passages or ports 13, which permit the ready displacement of air from the flanged head 4 in the carton-filling action.

It is desirable that the head 4, when applied to the shell 3 and interlocked thereto by the bayonet joints 5, be held against "back lash" or rotary motion in respect to the said shell, and this I accomplish in a simple manner by the use of a small lock lever or element 14, which, as shown, is pivoted to the head 4 and is provided at its free end with an offset nose or portion 15, which, under spring tension from said lever, will be yieldingly held in the space between the lug and the slot of the bayonet joint, as shown in Figs. 1 and 5. The outturned free end 16 of the lock lever 14 permits the same to be sprung laterally into an inoperative or releasing position when it is desired to remove the head from the shell.

25 What I claim is:—

1. A carton filler comprising a substantially cylindrical shell having a multiplicity of small air-venting ports leading from the inner surface thereof for breaking up partial vacuum existing between the carton and the surrounding shell, the greater part of the interior of said shell being intact so that it maintains the form of the carton under pressure and prevents the same from being forced into said air vents. 30

2. The structure defined in claim 1 in which said small air vents are in the form of narrow circumferentially spaced longitudinally extended air-venting channels. 35

3. A carton filler comprising a substantially cylindrical shell having a head detachably connected thereto by bayonet joints, and a lock in the form of a resilient lever pivoted to said head and having an offset free end insertable into the space between the lug and opposing wall of the slot of said bayonet joint to hold the said joint interlocked. 40 45

In testimony whereof I affix my signature.

BURTON L. HUNTLEY.
